DESIGN FOR COMBINED MATCH CLUSTERS AND HOLDER

Harry Cohen, Chicago, Ill.

Application May 4, 1942, Serial No. 106,789

Term of patent 7 years

To all whom it may concern:

Be it known that I, Harry Cohen, a citizen of the United States, residing at Chicago, in the county of Cook and State of Illinois, have invented a new, original, and ornamental Design for Combined Match Clusters and Holder, of which the following is a specification, reference being had to the accompanying drawing, forming part thereof.

Figure 1 is a front elevational view of combined match clusters and holder, showing my new design; and

Fig. 2 is a side elevational view thereof.

I claim:

The ornamental design for combined match clusters and holder, as shown.

HARRY COHEN.
